CLAIM

The ornamental design for a bone plate, as shown and described.

DESCRIPTION

FIG. 1 is a front, top perspective view of a bone plate comprising the new design;

FIG. 2 is a back, bottom perspective view of the design of FIG. 1;

FIG. 3 is a front elevational view of the design of FIG. 1;

FIG. 4 is a back elevational view of the design of FIG. 1;

FIG. 5 is a left elevational view of the design of FIG. 1;

FIG. 6 is a right elevational view of the design of FIG. 1;

FIG. 7 is a top view of the design of FIG. 1; and,

FIG. 8 is a bottom view of the design of FIG. 1.

The broken lines are directed to the environment and are for illustrative purposes only; the broken lines form no part of the claimed bone plate invention.

The relatively light uneven broken lines shown in the figures represent contour only.
